UNITED STATES PATENT OFFICE.

GEORGE T. CHERINGTON, OF WAUKEGAN, ILLINOIS.

DRIVE FOR PHONOGRAPH-GOVERNORS.

1,365,378.

Specification of Letters Patent. Patented Jan. 11, 1921.

Application filed May 26, 1920. Serial No. 384,319.

To all whom it may concern:

Be it known that I, GEORGE T. CHERINGTON, a citizen of the United States, and resident of Waukegan, county of Lake, and State 5 of Illinois, have invented a certain new and useful Improvement in Drives for Phonograph-Governors, of which the following is a specification.

My invention relates to that class of devices which are employed for driving centrifugal phonograph governors which are customarily driven by means of a worm and worm-wheel, or a worm and spiral-gear. As the governor has to travel at a very high 15 rate of speed, it results in the production of more or less noise which is seemingly unavoidable or very objectionable because of its interference with the sound waves of the music from the record, although numerous 20 attempts have been made to overcome this highly objectionable feature.

My invention has for its object to provide a drive which will be so noiseless in operation that it cannot be heard even at a 25 distance of a few inches. My means of accomplishing the foregoing object may be more readily understood by having reference to the accompanying drawings which are hereunto annexed and are a part of this 30 specification, in which—

The figure is a side elevation of a drive equipped with my improvement.

Similar reference numerals refer to similar parts throughout the entire description. 35 As shown in the drawings, the governor 1 is carried by the governor shaft 2, upon which is mounted a worm 3 adapted to mesh with the teeth of the worm-gear or wheel 4, driven by the motor of the phonograph (not 40 shown).

The governor is provided with the customary disk 5 for regulating its speed, by contacting with the brake 6 which is provided with the usual felt brake-shoe 7.

45 In utilizing my invention, the worm 3 is made of leather which is first thoroughly impregnated with oil and then with graphite. The worm is then cut, and if it appears that

the impregnating process has not succeeded any in causing the oil and graphite to penetrate deeper than the teeth which are hobbed in the worm, the process is repeated so as to produce a worm formed of leather which is completely impregnated with oil and graphite. The worm is then secured to the 50 governor shaft 2 and in mesh with the teeth of the worm-wheel 4.

I have demonstrated in practice that where other means are employed for this drive, the sound caused by the meshing of 60 the teeth when the governor is traveling at high speed, is distinctly audible at from five to fifty feet distance, according to the different kinds of material employed, whereas where my form of drive is employed, it is 65 impossible to detect the noise of the gears even when the ear is placed within a few inches of the device, with the result that there is no interference at all with the sound waves produced by the record, thus resulting in a highly improved machine.

Having described my invention what I regard as new and desire to secure by Letters Patent is:

1. A governor drive for phonographs comprising the combination with a governor having a shaft, of a worm mounted on said shaft, said worm being formed of leather which is impregnated with graphite and oil, and a worm-wheel to drive said worm. 75

2. A governor drive for phonographs comprising the combination with a governor having a shaft, of a worm mounted on said shaft, said worm being formed of leather which is impregnated with anti-friction ma- 85 terial and a means to drive said worm.

3. A governor drive for phonographs comprising the combination with a governor having a shaft, of a worm mounted on said shaft, said worm being formed of leather 90 which is entirely impregnated with graphite and oil, and a worm-wheel to drive said worm.

In testimony whereof, I have signed the foregoing specification.

GEORGE T. CHERINGTON.
